UNITED STATES PATENT OFFICE.

CHARLES S. S. BARROWS, OF IPAVA, ILLINOIS.

FRACTURE APPARATUS FOR USE WITH INVALID-BEDS.

No. 923,317.

Specification of Letters Patent.

Patented June 1, 1909.

Application filed November 17, 1906. Serial No. 343,923.

To all whom it may concern:

Be it known that I, CHARLES S. S. BARROWS, a citizen of the United States, residing at Ipava, in the county of Fulton and State 5 of Illinois, have invented certain new and useful Improvements in Fracture Apparatus for Use with Invalid-Beds, of which the following is a specification.

My invention relates to improvements in 10 fracture apparatus for use with invalid beds. Its objects are to provide for the ready suspension in comfortable or easy position of an injured limb or leg, especially when fractured, either above or below the knee.

15 Said invention consists of certain structural features or instrumentalities substantially as hereinafter fully disclosed and specifically pointed out by the claims.

In the accompanying drawing illustrating 20 the preferred embodiment of my invention the figure is a perspective view of the same.

In carrying out my invention, I employ an upright frame 1 which has its vertical members suitably connected preferably by inverted T-couplings or unions 2 to lateral base-members 3 arranged in lines at right-angles to the general plane of said frame. Said frame is also braced in position by short diagonally arranged rods or braces 4 suitably 25 held in place to the vertical members thereof and said lateral base-members. Said frame has also an extensible and contractible upper end portion comprising telescoping sections 5, 6 for the suitable adjustment thereof to 30 accommodate the width of the bed to which it may be applied. Suitably suspended from said upper end-portion 5, 6 of said upright-frame, by a bail a, lines or ropes 7 and pulley blocks 8, is a "cradle" 9, preferably a metal 35 trough-like contrivance or stirrup, for receiving and suspending the limb or leg which may be injured, especially when fractured or broken below the knee as will be readily appreciated; the patient or invalid presumably 40 lying in the bed in connection with which the device may be used. The upper pulley block is preferably hung directly from a hook 10 suitably rigged upon the upper end portion 45 of the upright-frame 1; the line or rope 7 aforesaid, rove through said block, as also 50 through the coöoperating pulley-block, being

hitched or looped around a cleat 11 fixed to one of the vertical members of said frame. Said "cradle" or stirrup 9 is suitably equipped with a foot-rest strap 12, its ends 55 being passed through lateral apertures therein, near the extreme outer end thereof, the strap, itself, being passed or stretched across said end as shown, in position to receive the bottom of the invalid's foot. 60

An additional upright frame 27, having attached to its lower ends lateral extension-plates or bars 28 embracing, or striding the base-members 3, is also provided for suspending in position, or the employment of a 65 second sling, "cradle" or stirrup 29, for use in event of the fracture or injury extending above the knee, said stirrup or "cradle" being conjointly used with the aforesaid sling, stirrup or "cradle" for forming an extended 70 support for the leg. Said additional upright frame is also equipped with a like hook 30 for suitably engaging therewith and supporting in position a pulley-block 31, over whose pulley and the pulley of a second pulley-block 32 is rove a line or rope 33 suitably connected to a bail 34 attached to said second stirrup or "cradle", said rope or line being suitably passed or looped around a cleat 35 fixed to 75 said upright frame. Said second stirrup or 80 "cradle" has at one end a hook 36 effective for engagement with one of the lateral holes in the aforesaid stirrup or cradle, receiving the foot-rest strap thereof, the latter now being removed and applied to the additional 85 stirrup or sling as shown in Fig. 2. Said additional upright frame is also provided with an extensible and contractible upper end portion for the like purpose as that of the corresponding part of the aforesaid upright 90 frame and suitably sustained in upright position by means of buckle-equipped straps 37 passed or looped around the upper end portions of the two upright frames as shown.

I claim—

1. A device of the character described, comprising an upright frame or support, an additional like support both held upon a common base, stirrups or slings suspended from said frames respectively, suspending means therefor, and means connecting together said stirrups or slings. 95

2. A device of the character described, comprising a plurality of upright supports one fixed to a common base and the other removable from the latter, means connecting said supports together, stirrups or slings suspended from said supports, and suspending means for said stirrups or slings, and means for connecting together said stirrups em-

bracing a hook attached to one stirrup and engaging the opposite stirrup. 10

In testimony whereof I affix my signature, in presence of two witnesses.

CHARLES S. S. BARROWS.
